United States Patent Office

Des. 193,687
Patented Sept. 25, 1962

193,687

JUG

Kenji Yoshizumi, 4980 N. Marine Drive, Chicago, Ill.

Filed Feb. 15, 1962, Ser. No. 68,842

Term of patent 14 years

(Cl. D58—5)

FIG. 1 is a front elevational view of a jug showing my new design;

FIG. 2 is a side elevational view thereof;

FIG. 3 is a side elevational view thereof;

FIG. 4 is a top plan view thereof;

FIG. 5 is a bottom plan view thereof.

The rear not shown is the same as the front view which is shown.

I claim:

The ornamental design for a jug, substantially as shown and described.
